UNITED STATES PATENT OFFICE.

CARL E. ANDERSON, OF BRIDGEPORT, CONNECTICUT, ASSIGNOR TO THE PERKINS ELECTRIC SWITCH MFG. COMPANY, OF BRIDGEPORT, CONNECTICUT, A CORPORATION OF CONNECTICUT.

SWITCH-HANDLE.

946,309.

Specification of Letters Patent. Patented Jan. 11, 1910.

Application filed August 17, 1909. Serial No. 513,304.

To all whom it may concern:

Be it known that I, CARL E. ANDERSON, a citizen of the United States of America, and residing at Bridgeport, in the county of 5 Fairfield and State of Connecticut, have invented a certain new and Improved Switch-Handle, of which the following is a specification.

My invention relates to switch handles, 10 particularly to handles for rotary snap switches, the object of my invention being to render the removal of the handle from the switch spindle more difficult.

In the accompanying drawings in which 15 my invention is illustrated, Figure 1 is a vertical elevation, partly in section, showing a switch handle with parts detached, in which my invention is embodied in one form; Fig. 2 is a vertical section thereof, with parts assembled; Fig. 3 is a horizontal section on the line 3—3, Fig. 2; Fig. 4 is a view similar to Fig. 1 of a switch handle in which my invention is embodied in another form; Fig. 5 is a vertical section thereof, parts assembled; 25 Fig. 6 is a horizontal section on the line 6—6, Fig. 5; and Fig. 7 is a plan of a washer employed in the latter form.

It has been found that switch handles, such as that described in Goodridge 835,278, are 30 frequently accidentally unscrewed from the switch stem by turning in the wrong direction, and that meddlesome or vandalous persons find it easy to remove the handle and thus render the switch temporarily inoperative. Furthermore upon the removal of the 35 handle the cover of the switch may be easily taken off and the switch parts thereby dangerously exposed.

To render the removal of the handle more 40 difficult, I propose to insert a ratchet or equivalent mechanism between the handle and the stem, so that when the handle is turned in one direction the switch is operated, while when the handle is turned in 45 the opposite direction, it revolves freely upon the switch spindle without becoming detached therefrom. In the embodiment of this idea shown in Figs. 1 to 3, the body A of the handle which is preferably molded of 50 suitable insulating material, is formed with a polygonal recess *a* extending from below up into the body. As shown, this recess is hexagonal in cross section. Working in this recess is a plunger B with shoulder *b*, the 55 upper face of which is toothed to serve as a

ratchet member coöperating with the superposed independent ratchet member *b*¹. The latter is formed of hexagonal section corresponding to that of the recess *a*, so as to turn with the handle, while the lower member *b* does not engage the sides of the recess. Through a perforation of the member *b*¹ passes the spindle *s* at the head of the plunger, which not only centers the upper member *b*¹ with relation to the lower member *b*, but also serves as a guide for the ratchet spring S. The stem of the plunger is encircled by a spiral spring M bearing at its upper end against the lower face of the ratchet member *b* and at its lower end against the retaining cup C which is secured in customary manner to the hub *a*¹ surrounding the mouth of the recess *a*. The plunger is internally threaded as usual to receive the upper end of the switch spindle P. 75

It will be observed that when the handle is turned in one direction the switch spindle is rotated through the ratchet, while by reason of the latter, when the switch handle is turned in the opposite direction, not only 80 is the switch spindle not affected, but neither is there any tendency to unscrew the handle. To accomplish the latter it is necessary to lift the handle body against the action of the spring M, until the plunger is so far exposed that it may be grasped by a pair of 85 pliers and then unscrewed by means of the same.

In the second form, illustrated in Figs. 4 to 7, the construction is the same in essential features, but here the upper portion *x* of the plunger is given a polygonal shape and a washer *y* with corresponding polygonal perforation is inserted beneath the spring M, so that when the handle body is 90 lifted as described, the angled recess of the washer engages the angled portion of the plunger. Upon turning the handle while the parts are in this position, the plunger may be unscrewed from the switch spindle. 95 In this modification, the upper ratchet member *b*¹ is made heavier and is recessed from above to form a seat for the ratchet spring S. 100

Obviously the construction may be variously modified to accomplish the same purpose and I do not limit myself to the precise structure shown, but claim as my invention:— 105

1. In a switch handle, means for securing said handle to a switch spindle and means 110

interposed between the body of said handle and said securing means whereby said handle is free to rotate in one direction without affecting either said securing means or the switch spindle.

2. In a switch handle, means for securing said handle to a switch spindle and a ratchet interposed between the body of said handle and said securing means whereby said handle is free to rotate in one direction without affecting either said securing means or the switch spindle.

3. In a switch handle, means for securing said handle to a switch spindle and means interposed between the body of said handle and said securing means whereby said handle is free to rotate in one direction without affecting either said securing means or the switch spindle, the body of said handle be-

ing displaceable axially to afford means for 20 freeing said handle from the switch spindle.

4. In a switch handle, means for securing said handle to a switch spindle and means interposed between the body of said handle and said securing means whereby said handle is free to rotate in one direction without affecting either said securing means or the switch spindle, together with means, operative upon the axial displacement and rotation of the body of said handle, for freeing 30 said handle from the switch spindle.

In testimony whereof I have signed my name to this specification, in the presence of two subscribing witnesses.

CARL E. ANDERSON.
